UNITED STATES PATENT OFFICE.

EDGAR L. ESHLEMAN, OF ROCHESTER, NEW YORK.

PORTABLE MUSIC HOLDER.

Application filed February 21, 1927. Serial No. 169,893.

My present invention comprises a holder for music which is especially useful for piccolo or fife players as it can be attached to and firmly supported on the arm of the 5 musician to constantly hold the music in the proper position with relation to the instrument as well as the line of vision of the musician when playing the instrument while marching. The support of the music is thus 10 not affected by any irregular movement of the body of the musician when marching over uneven ground.

These and other features and objects of this invention will be fully illustrated in 15 the drawing, described in the specification and pointed out in the claims at the end thereof.

In the accompanying drawing:

Figure 1 is a perspective view of the music 20 holder.

Figure 2 is a top plan view of the holder.

As illustrated in these figures the holder is mainly bent up from metal rod stock of suitable thickness that will form a support 25 having the proper rigidity and provide sufficient spring tension to clamp itself in place on the arm.

The holder is formed to provide two loops 1 and 2 that hook over the left arm at an 30 angle to each other so that loop 1 of the supporting end of the holder can be slipped over the lower end of the upper arm and loop 2 over the beginning of the lower arm with the elbow located between the two loops 35 as illustrated in dotted lines in both of the figures.

A third elongated loop 3 which connects the loops 1 and 2 forms a vertical flat bracing member that projects downwardly from the 40 arm and normally rests against the body so as to hold the holder against turning on the arm. This function of the elongated loop 3 in holding the holder against turning on the arm is supplemented by the finger 4 projecting 45 from the free end of the loop 1. This finger extends rearwardly of the loop 1 and is located partly under the arm to exert a pressure on the arm that will clamp the loop 1 in place on the arm. Furthermore this 50 rearward extension of the holder which is practically parallel with the upper arm, serves to brace the holder from underneath and prevent its tilting downwardly in front of the arm. This will be apparent from an 55 inspection of Figure 2 in which the supporting arm 5 and the loops 1, 2 and 3 of the

holder are illustrated in their proper position with relation to each other. The supporting arm 5 projects away from the body of the musician while the finger 4 projects 60 rearwardly underneath the upper arm and parallel thereto. An eye 6 is formed on the end of the finger 4 which increases the contact area of the finger with the arm and serves to increase the hold of the finger on 65 the arm.

On the outer end of the supporting arm 5 is carried the clamp 7 by means of which sheets of music or a book of music may be fastened thereto and held in front of the 70 musician in line with his vision while playing the piccolo or fife when marching. To illuminate the music at night the holder is provided with a flash light 8. The body of this flash light is provided on one side with 75 the angular sleeve 9 which is adapted to telescope over the upwardly and rearwardly projecting pin 10 carried on top of the loop 2 of the holder. A spring finger 11 in the form of a loop is also carried on top of the holder 80 behind the pin 10 and forms a stop against which the body of the flash light 8 can rest to assume its proper position with relation to the holder. The light from the flash light is directed toward the clamp of the holder 85 so that any music supported thereby will be properly illuminated. The switch 12 of the flash light is so arranged that it can be readily reached by the musician and turned on or off as needed. 90

I claim:

1. A portable music holder comprising a pair of loops disposed angularly to each other and open at the bottom, a bracing member connecting said loops on one side thereof, a supporting arm projecting from one of said loops and a clamp carried by said supporting arm. 95

2. A portable music holder adapted to be attached to the arm comprising a pair of loops disposed angularly to each other and adapted to hook over the arm, a bracing member connecting said loops on one side thereof, a supporting arm projecting from one of said loops and a clamp carried by 100 said supporting arm, a rearwardly extending finger projecting from the other of said loops and adapted to project under the arm in engagement therewith to clamp the holder in place on the arm. 105

3. A portable music holder adapted to be attached to the arm comprising a pair of 110

loops bent from rod stock and having their bottom open and disposed angularly to each other to engage over the bent arm with the elbow located between the pair of loops, a 5 third loop connecting said pair of loops on one side thereof and forming a vertical brace therefor to prevent said pair of loops from turning on the arm on which they are supported, a supporting arm projecting from 10 one of said pair of loops, a clamp carried on the outer end of said supporting arm.

4. A portable music holder adapted to be attached to the arm comprising a pair of loops bent up from rod stock and having their bottom 15 open and disposed angularly to each other adapted to engage over the bent arm with the elbow located between the pair of loops, a third loop connecting said pair of loops on one side thereof and forming a vertical brace therefor to prevent said pair of loops from turning on the arm on which they are supported, a supporting arm projecting from one of said pair of loops, a clamp carried on the outer end of said supporting arm, a supporting 20 bracket provided on said 25 arm, a supporting bracket provided on said

loop ahead of said supporting arm and adapted to be supported thereon in line with said supporting arm, a flashlight.

5. A portable music holder adapted to be attached to the arm comprising a pair of loops having their bottom open and disposed angularly to each other to engage the bent arm with the elbow located between the pair of loops, a bracing member connecting said pair of loops on one side thereof to prevent said pair of loops from turning on the arm on which they are supported, a supporting arm projecting from one of said pair of loops, a clamp carried on the outer end of said supporting arm, a supporting bracket on said supporting arm comprising a rearwardly projecting pin adapted to support a flashlight in line with said supporting arm, a finger on said supporting arm on one side of said supporting bracket adapted to hold a flashlight in a predetermined position on said supporting bracket. 30 35 40 45

In testimony whereof I affix my signature.

EDGAR L. ESHLEMAN.
